UNITED STATES PATENT OFFICE

2,137,803

CHAIR TIP AND FASTENER THEREFOR

George W. Hambrook, Oak Park, Ill., assignor to
 Clarin Mfg. Co., Chicago, Ill., a corporation of
 Illinois

Application May 16, 1938, Serial No. 208,156

6 Claims. (Cl. 45—137.1)

This invention pertains to chair tips of the kind typically shown in Letters Patent to Grant, No. 1,789,974, dated January 27, 1931, and consisting of a foot in the form of a block of solid rubber or other flexible material and a fastener for securing the foot to the lower end of a chair leg. In the structure disclosed in the said patent the tip is used on a metal chair leg which has hollow beads on its longitudinal edges, and the fastener 10 consists of a U-shaped yoke bent to shape from a section of round rod stock, the base and lower portions of the arms of the yoke being embedded in the foot and the projecting portions of the arms being driven into and frictionally engaged 15 with the beads of the chair leg.

An extended manufacturing experience with this type of chair tip by my assignee has disclosed some faults therein, which it is the object of the present invention to remedy. In the first 20 place, the base member of the yoke being of round cross-section, when the lower portion of the foot wore off exposing the base of the yoke, the latter would make dents and grooves in the surface of the floor. In the second place, in order to prevent the lower end of the chair leg from cutting 25 down into the rubber foot it was found necessary to insert metal washers on each arm of the yoke between the beads of the leg and the top of the foot, which added to the cost; and in the third 30 place, the embedded portion of the yoke, being of round cross-section and smooth external surface lacked a secure grip on the rubber foot such as to prevent relative movement between the two.

The improved fastener of the present invention 35 has a wide flat imperforate base that will not dent, score, or otherwise mar the surface of the floor if brought into contact therewith; the arms are formed with stop shoulders that limit the penetration of the beads of the chair leg into the 40 foot, and thus do away with the metal washers heretofore used; and the yoke being of rectangular cross-section throughout, and preferably made as a metal stamping, has a secure grip on the foot that prevents any looseness of fit or 45 relative movement of the foot and the yoke.

A preferred embodiment of the invention is illustrated in the accompanying drawing, in which—

Fig. 1 is a perspective view of the novel fastener yoke.

Fig. 2 is a top plan view of the same.

Fig. 3 is a side elevation of the same.

Fig. 4 is a perspective elevation of the lower portion of a chair leg with the rubber foot attached thereto.

Fig. 5 is a vertical longitudinal section through the leg and foot on line 5—5 of Fig. 8.

Fig. 6 is a vertical transverse section on line 6—6 of Fig. 5; and

Figs. 7 and 8 are horizontal sections on lines 5—7 and 8—8 respectively of Fig. 5.

Referring to the drawing and first describing parts that are old and disclosed in the aforesaid Grant patent, 10 designates as an entirety a metal leg of a foldable chair which is made from 10 a strip of suitable sheet metal, the longitudinal edge portions of which are rolled to form parallel tube-like edges or beads 11. 12 designates the foot, which is preferably a solid block of vulcanized rubber.

The foot is attached to the chair leg by an improved fastener yoke in which the novelty of the present invention mainly resides. This yoke is preferably die-stamped from a flat strip of suitable metal, such as soft steel, and is then bent 20 to the general U-shape shown in Figs. 1, 3 and 5. The form of the die is such as to create a pair of arms and a transverse connecting member or base. When the device is bent to finished shape the arms are substantially parallel, and the upper 25 main portions 13 thereof that are driven into the beads 11 are narrower than the lower portions 13' thereof and the flat base 14 that are embedded in the rubber foot 12 prior to vulcanizing the latter. At the mergence of the relatively narrow and 30 wide portions 13 and 13' of the arms are formed shoulders 15 that normally lie slightly below the top surface of the foot 12, as shown in Figs. 5 and 6.

The upper end of one leg portions 13 is bent 35 inwardly as shown at 16, and the distance between the free end of this bend 16 and the upper end of the other leg portions 13 is slightly less than the distance between the walls of the beads engaged by said ends, so that the arms of the 40 fastener yoke are slightly expanded as they are driven into the beads and have a friction bite or grip on the internal walls of the beads at the points a, b, c, and d (Fig. 7), amply sufficient to prevent the foot from dropping off the leg when 45 the latter is raised to take the foot off the floor.

The base member 14 of the yoke has a wide, flat, smooth imperforate bottom surface, so that if or when the rubber foot wears down sufficiently to expose said surface it will not dent, groove or 50 otherwise mar the surface of the floor, but will act as a glider.

The main function of the shoulders 15 is that of a stop to limit the extent to which the lower ends of the beads can cut into the rubber foot. 55

Obviously, they take the place of, and render unnecessary, the metal washers 5 of the aforesaid Grant patent. And since the upper portion of the rubber foot is molded over said shoulders, the latter aid in locking the foot onto the portion of the yoke embedded therein.

The fact that the fastener yoke is of rectangular cross-section throughout gives it certain advantages over a similar yoke of round cross-section. It presents greater resistance to any tendency of the foot to slip or turn locally on the base of the yoke when the foot may be dragged sideways over the floor; due also to the substantial width of the base member 14 the latter strongly resists any tendency of the foot to cant or tilt sidewise relatively to the chair leg; and the rectangular cross-section of the arms creates comparatively sharp point contacts of the arms on the walls of the beads that strongly oppose any relative sliding movement.

Detail variations from the specific form of the improvement shown in the drawing may be resorted to within the scope of the appended claims.

I claim:

- 25 1. A chair tip of the class described, comprising a foot, and a fastener for securing the same to the lower end of a chair leg having hollow beads on its longitudinal edges, said fastener comprising a U-shaped metal member having arms 30 adapted to fit frictionally in said beads and a flat bottomed base of greater width than the bead engaging portions of said arms, said base and the lower portion of said arms being embedded in said foot.
- 35 2. A chair tip of the class described, comprising a foot, and a fastener for securing the same to the lower end of a chair leg having hollow beads on its longitudinal edges, said fastener comprising a U-shaped metal member having 40 arms adapted to fit frictionally in said beads and a flat bottomed base, said base and the lower portions of said arms being of greater width than

the portions of said arms engaged with said beads and being embedded in said foot.

3. A chair tip of the class described, comprising a foot, and a fastener for securing the same to the lower end of a chair leg having hollow 5 beads on its longitudinal edges, said fastener comprising a U-shaped metal stamping of rectangular cross-section throughout having relatively narrow arms adapted to fit frictionally in said beads and a relatively wide flat base, said 10 base and the lower portions of said arms being embedded in said foot.

4. A chair tip of the class described, comprising a foot, and a fastener for securing the same to the lower end of a chair leg having hollow 15 beads on its longitudinal edges, said fastener comprising a U-shaped metal stamping of rectangular cross-section throughout having relatively narrow arms and a relatively wide flat base, said 20 arms formed with stop shoulders limiting the penetration of said beads into said foot, and said base, said shoulders, and the portions of said arms therebetween being embedded in said foot.

5. As a new article of manufacture, a one-piece fastener for securing a foot to the lower end of 25 a chair leg, comprising a U-shaped metal stamping of rectangular cross-section throughout having relatively narrow arms and a relatively wide flat base integrally connecting the lower ends of 30 said arms.

6. As a new article of manufacture, a one-piece fastener for securing a foot to the lower end of a chair leg, comprising a U-shaped metal stamping of rectangular cross-section throughout having 35 arms formed with relatively narrow upper portions, widened lower portions, and stop shoulders at the junction of said upper and lower portions, and a flat base integrally connecting said lower portions and of the same width as the latter.

GEORGE W. HAMBROOK.
